UNITED STATES PATENT OFFICE.

ATTILIO PIERINI, OF SPRINGFIELD GARDENS, NEW YORK; ARTHUR T. HOPKINS, OF CAMBRIDGE, AND HARRY M. HAVEN, OF WINCHESTER, MASSACHUSETTS.

APPARATUS FOR DRYING FUR PELTS.

Application filed February 3, 1927. Serial No. 165,655.

The present invention is an apparatus for drying dyed fur pelts and skins, and has for its main object rapid drying of large quantities of skins in such a manner that the wet fur surfaces thereof are quickly and thoroughly dried and the skin pelts are dried to the extent and in such a manner that they will not become hard and brittle so as not to crack or become too stiff for commercial purposes or to be worked.

With the above and other objects in view the invention resides in sundry details of construction, combination and arrangement of parts hereinafter more fully described and pointed out in the appended claims.

The accompanying drawings illustrate and the specification describes the invention in the form in which it is considered to be the best, but the invention is not limited to such form therein described, because it is capable of being embodied in other forms; but it is to be understood that in and by the claims following the description herein, it is intended to cover the invention in whatever form it may embody or be practiced within the scope thereof.

In the drawings which show the preferred embodiment of the drying apparatus as at present devised:

30 Figure 1 is a plan view of the drying apparatus;

Figure 2 is a side elevation of the invention as illustrated in Figure 1;

35 Figure 3 is a longitudinal sectional view of the dryer as illustrated in Figures 1 and 2 to show the interior thereof;

Figure 4 is a transverse sectional view taken substantially on line 4--4 of Figure 3;

40 Figure 5 is a fragmentary longitudinal sectional view through the entrance of the drier.

Throughout the drawings and specification like reference characters denote similar and like parts wherever referred to.

45 With particular reference to the drawings, the drying apparatus of this invention comprises mainly of an elongated drying chamber or tunnel which may be for convenience, but not necessarily, suspended from the ceiling of a room to lie overhead and occupy space not otherwise ordinarily used.

The tunnel or conduit 1 is preferably constructed of galvanized iron, or suitable like material, lined on its inner surface with an insulating material, which has its inner sur-

face covered with a facing, preferably plaster, thus retarding the heat radiation and causing a substantial uniform temperature within the drying chamber.

The conduit 1 is a closed tunnel-like construction, but is here shown as being substantially rectangular in cross-section, with its forward or receiving end closed by an end wall 2 provided with a restricted entrance opening 3 and its other end portion reduced and suitably formed to provide a suitable casing for a rotatable fan blower.

The major portion of the conduit extending from its forward end provides what is termed the drying chamber A, and has its 70 bottom wall or floor 4 flat and smooth (composed preferably of $\frac{1}{8}$ maple with smooth sand-papered finish), supported on two parallel channel irons 5 running the entire length of the drying chamber. The channel 75 irons are supported in position by the vertical support members 6, which may be suspended from the ceiling or the like, and also support on their underside the bearing blocks 7 in which the idle support rollers 8 80 and 8' are journalled.

At the rear end of the channel members 5, where the floor or lower wall 4 of the drying chamber A terminates, the bottom of the conduit is off-set inwardly, as at 9, clearly shown in Figures 2 and 3, to provide an outlet or discharge opening 10. Rearwardly of the off-set portion 9, is the heating chamber B in which is disposed a heating unit H, composed of steam-heated coils of a type 90 which may be slid into and out of position through a side opening in the conduit when the joints or couplings 11 are disconnected. At the rear of the chamber B, the conduit has its side wall converging to produce a fan 95 blower casing C in which is journalled a suitable fan blower F.

A conveyor belt 12 is extended through the opening 3 in the conduit and is supported by and passes over the floor 4, thence 100 through the outlet or discharge opening 10 around a drive roll 8' and back under the bottom wall or flooring 4 of the conduit where it engages and is supported at intervals by other idle rollers 8. The belt or conveyor 12 is of a continuous or endless type and from the entrance opening 3 is extended downwardly, as indicated in Figures 2 and 3, to a table 13 where it passes over other idle and spacing rolls 8''. The 110

lower end of the endless belt 12, is caused to travel in a horizontal plane by reason of the idle rollers 8" being disposed in a horizontal plane so that when skins or pelts are placed on the portion 14 of the belt they will travel upwardly to the dryer. This vertical lifting by the belt 12 is accomplished in co-operation with a second endless belt 15 which is arranged in juxtaposition with the carrying or supporting surface of the vertical portion of the belt 12, the belt 15 passing over suitably arranged idle rollers 16 supported on the table 13 and over the rollers 17 journaled at the forward end of the conduit and supported by the channel members 5. The belt 12 is held taut by a weighted roller 18 slidably journaled in a vertical slot 19 in one leg 20 of the table 13, suitable weights 21 being suspended from the roller, 20 The belt 15 in like manner is held taut by weights 22' secured to a chain 22 passing over sheaves 23 and connected with the roller 17' which is slidably mounted as indicated by the dotted-line in Figure 2.

25 The drying chamber A is designed to be of any desirable length, however, the ones now in use are of approximately 125 feet long and 6 feet wide and have drying capacity of about 600 rabbit skins per hour.

30 The drying is accomplished by a current of heated air emanating from the fan blower F and passing through the heater H from whence it traverses the entire length of the drying chamber A in a direction opposite to the direction of the movement of the skins therethrough. It will thus be seen that the dry heated air coming from the heating chamber B first acts upon the skins which have been subjected the longest to the drying operation and thereby more quickly absorbs the moisture therefrom to complete the drying operation and then passes progressively over less dried skins.

45 Upon reaching the forward end of the drying chamber, the heated air is diverted by the end wall 2 into the lateral ducts 24 on the opposite sides thereof which are connected with a return conduit 25 underlying for a distance the drying chamber A and then is off-set laterally, as at 25', and connected at its rear end to the fan casing C whereby the heated air may be recirculated.

50 In the operation of the device, very little of the air will be lost through the opening 3 as this opening will be partially closed by the fur pelts entering the same and by reason of the suction from the fan F in the conduits 24 and 25.

55 After the fur pelts have traversed the length of the drying chamber A on the belt 12 they are passed through the outlet opening 10 at which point they drop from the belt into a chute 26 and are delivered to a suitable basket or receptacle 27 arranged at 60 or adjacent the floor.

From the device at present illustrated, the front end portion of the return conduit 25 is shown as a structural part of the front plate 2 and as supported therefrom. However, the conduit may be supported in any suitable or approved way.

65 Doors 28 are provided in the side walls of the conduit 1 at intervals along the length for the purpose of permitting access to the interior thereof. The return air conduit 25 is provided at its forward end with a damper 29, which when open will cause part of the returning air to be discharged from the device, and at its rear end with a damper 30 adjacent the fan F, which when open will permit fresh or cooled air to be drawn into the apparatus. The dampers 29 and 30 may be actuated to suit the operating conditions and the particular desires and requirements for the material being treated, and as a means for regulating the temperature of the air in the apparatus. The said dampers may be held in adjusted position by any suitable means, such as by the usual segmental rack 31.

70 The belt is driven from driving roller 8' which has a pulley 32 fast thereon and which is connected up with any suitable drive mechanism 40 preferably actuated by a motor 41. In order to vary the speed of the belt 12, a combination of pulleys may be provided which will accomplish this purpose, although any other desired means 42 may be provided. The fan F is preferably driven by an independent electrical motor 100 suspended from a supporting bracket 33 also supporting the rear end of the conduit. The driving mechanism of the belt 12 is, preferably, arranged at the dry end of the drying chamber, thereby protecting the actuating means from the moisture which prevails in greater degree at the forward end of the drying chamber.

75 The above apparatus accomplishes the aims of the method of the invention, that is, drying the fur surfaces of the pelts quickly and thoroughly while the skin surfaces are dried gradually and are protected from the intense heat which will tend to harden the skins and cause them to be too brittle to be worked or for commercial purposes. These aims are accomplished according to the present method by placing the skin surfaces of the pelts against the conveyer belt 12 so that, when the same is delivered to the entrance 3 of the drying chamber, the fur surface of the pelts are uppermost and are subjected to the heated air currents passing thereover, the fur surface of the pelts and the belt 12 (in engagement 125 with floor surface 4) protecting the intermediately positioned skins from drying too quickly or to too great extent, while the fur will be drying quickly and thoroughly.

80 Having thus described the preferred em- 130

bodiment of the invention, as at present devised, and in what manner the same is to be performed, that which is claimed as new and novel is:

5 1. A drying apparatus comprising an elongated conduit having an entrance at one end and an air inlet at the other end from which an air current is introduced into the conduit, a conveyer in said conduit to move 10 the material to be dried from said entrance to a material discharge opening intermediate the length of said conduit, and a heating element interposed between said point of discharge in the conduit and said air inlet opening, and air return means connected to the 15 forward and rear end portions of said conduit whereby said air currents may be recirculated through said conduit, controlled means in said return means for discharging 20 a portion of the air therefrom and other controlled means in said return conduit for admitting fresh air thereto, and means for circulating said air.

2. A drying apparatus comprising an enclosed elongated conduit having a material entrance opening at one end portion and a material discharge opening at an intermediate portion thereof, a supporting frame underlying said conduit between said entrance 25 opening and discharge opening, supporting rollers journaled in said frame and under said conduit, an endless conveyer disposed to move over the bottom wall of said conduit from said entrance opening to said discharge 30 opening, whence passing through said discharge opening over said supporting rollers to said entrance opening, means for actuating one of said rolls whereby the belt is 35 operated, and means at the other end of 40 said conduit for introducing air thereinto.

3. A drying apparatus comprising an enclosed elongated conduit having a material entrance opening at one end portion and a material discharge opening at an intermediate portion thereof, a supporting frame underlying said conduit between said entrance 45 opening and discharge opening, supporting rollers journaled in said frame and under said conduit, an endless conveyer disposed to move over the bottom wall of said conduit from said entrance opening to said discharge 50 opening, whence passing through said discharge opening over said supporting rollers to said entrance opening, means for actuating one of said rolls whereby the belt is 55 operated, the other end portion of said conduit having its walls converging to pro-

vide a fan blower casing, and a fan mounted in said casing.

4. A fur pelt drying apparatus comprising an elongated horizontal conduit having a heat insulated wall, an entrance at one end and an air inlet at the other end from which an air current is introduced into the conduit, a belt conveyor resting on said wall 60 in said conduit to receive and move the pelts with the fur portion uppermost and the skin portion in juxtaposition with the conveyor, whereby the fur portion is subjected to the drying currents and the skin portion protected from too intensive drying, said conduit having a material discharge opening 65 intermediate the ends thereof.

5. A fur pelt drying apparatus comprising an elongated conduit having an entrance at one end and an air inlet at the other end from which an air current is introduced into the conduit, one wall of said conduit being adapted to support the pelts 70 during the drying and having the same moved thereover, conveyor means for moving said fur pelts over said wall from said entrance to a material discharge opening with the fur portion innermost and exposed 75 to the drying currents and the skin portion outermost and adjacent to said wall, whereby the skin portion is protected by said wall against drying hard and brittle.

6. A fur pelt drying apparatus comprising an elongated conduit having an entrance at one end and an air inlet at the other end from which an air current is introduced into the conduit, one wall of said conduit being adapted to support the pelts 90 during the drying and having the same moved thereover, conveyor means for moving said fur pelts over said wall from said entrance to a material discharge opening with the fur portion innermost and exposed to the drying currents and the skin portion outermost 95 and adjacent to said wall, whereby the skin portion is protected against drying hard and brittle, said discharge opening being intermediate the length of said conduit, the air inlet end of the conduit having its walls 100 converging, and an air current producing means connected to the end of said converging walls.

In testimony whereof we have hereunto set our hands.
